BEARING TRIMMER TABLE

Lee Brooks, Los Angeles, Calif.

Application June 8, 1931. Serial No. 542,920

4 Claims. (Cl. 90—58)

This invention relates to and has for an object the provision of a machine for trimming the flat surfaces of halved journals or bearings such as are employed for rotatably supporting automobile crank shafts and the like.

Another object is to provide a bearing trimming machine provided with relatively stationary and adjustable flat top portions and a cutter operating therebetween, together with means for adjusting said adjustable portion and the cutter simultaneously and to a common extent above the level of the stationary portion, whereby when the bearing is positioned with its flat surface on the stationary portion the same may be moved over the cutter and trimmed to an extent corresponding to the difference in elevation between the stationary and adjustable portions of the top.

A further object is to provide a conveniently arranged, simple, compact machine of light weight and durability which may be readily operated by skilled or unskilled persons alike for the purpose of trimming bearings, especially when the removal of shims from the bearings will not suffice to take the bearings up sufficiently for practical operation of a crank shaft therein.

Other objects may appear as the description progresses.

30 In the accompanying drawing I have shown a form of my invention subject to modification within the scope of the appended claims, without departing from the spirit thereof. In said drawing,

35 Fig. 1 is a top plan view of the assembled machine.

Fig. 2 is a transverse section of the same on line 2—2 of Fig. 1.

40 Fig. 3 is a sectional elevation of the same on line 3—3 of Fig. 2.

Fig. 4 is a fragmentary section on line 4—4 of Fig. 1.

Fig. 5 is a fragmentary section on line 5—5 of Fig. 1.

45 The machine includes a stationary frame 1 and a movable frame 2 adjustably mounted thereon, a rotatable cutter 3 and a motor 4 operatively connected with and supported on the adjustable frame 2, an adjusting element 5 serving to adjust the frame 2 on the frame 1, and a rotatable adjusting screw 6 mounted on the frame 1 and connected with the element 5, all arranged as shown and hereinafter described.

The frame 1 has a base portion 7 adapted to 55 rest upon a suitable supporting surface, and a

flat top 8 connected with the base by means of a plurality of legs 9, 9 etc. The frame 2 has a flat base 10 and a flat top 11 connected by legs 12, 12 etc., and the motor 4 is mounted on the base 10 of frame 2, while the top 11 carries the 60 rotatable cutter 3 held on a shaft 14, which is journaled in bearings 15, 15 secured to the lower side of the top 11.

The cutter is operated from the motor 4 by means of a belt 16 which runs over pulleys 17 and 18 carried on the motor shaft 19 and the cutter shaft 14 respectively.

By reference to Fig. 1 it will be noted that the top 11 of the adjustable frame 2 is of peculiar configuration and is vertically slidable in the 70 stationary top 8 of frame 1. The adjustable top 11 has projections 20, 20 on one side thereof which fit corresponding portions of the opening in the top 8 while the top 8 has corresponding or differently formed projections 21, which fit similar recesses in the adjustable top 11, whereby the top 11 may be guided in its vertical movement in and relative to the top 8. The periphery of cutter 3 is adapted to be substantially tangent to the upper face of the adjustable top 11, and an opening 80 22 is formed in the top 11 to receive said cutter.

The adjusting element 5 is of U shape as illustrated in Fig. 1, and includes a longitudinal portion 23 with legs 24 which underlie opposite portions of the adjustable top 11 and have flat horizontal lower surfaces and inclined upper surfaces, as at 25. The opposite end portions of the adjustable top 11 are provided with grooves 26, 26 which are inclined to correspond to the angularity of the wedges 24, 24 on the member 5.

The frame 1 supports a pair of bars 27, 27 which are attached to the lower side of top 8 by means of cap screws or bolts 29, 29 and serve as supports for the adjusting element 5. Thus, as seen in Fig. 4, the adjustment of the wedges 24 horizontally between the top 11 and the bars 27, 27 will serve to elevate or lower the adjustable frame 2 so as to elevate to a desired extent the top 11 and the cutter 3 above the upper surface of the top 8.

The longitudinal portion 23 of member 5 has a depending lug 30 thereon in which one end of the adjusting screw 6 is threaded, while the other end of said screw is rotatably held in a depending bearing 31 on the frame 1. A hand wheel 105 32 with a micrometer adjustment 33 is provided on the outer end of screw 6 so that the member 5 may be adjusted with exactitude and precision for correspondingly elevating or depressing the adjustable top 11 relative to the stationary top 8.

The base 10 of the adjustable frame 2 is vertically adjustable between the longitudinal ribs 34, 34 and intersecting transverse ribs 35, 35 formed centrally of the base 7 of frame 1. Thus the adjustment of the frame 2 by means of the hand wheel 32 will simultaneously adjust the motor 4, cutter 3 and top 11 vertically with respect to the stationary top 8 of frame 1.

In operation, a bearing of the character shown in Fig. 2 is placed on the stationary top 8 and the top 11 is adjusted by means of hand wheel 32 to a position above the surface of top 8 to correspond to the thickness of a cut to be taken from the lower flat surface of the bearing, whereupon the motor is energized and as the cutter is rotated the bearing is moved inwardly over cutter 3 and onto the movable top 11, and the bearing is trimmed nicely and smoothly to correspond to the extent to which the bearing is to be taken up.

What I claim is:

1. A bearing trimmer comprising a frame having a stationary table provided with an opening, a vertically adjustable top mounted in said opening and formed with inclined surfaces on the lower side thereof, and a horizontally adjustable member movably supported on said frame and having parallel portions with inclined upper surfaces engaging the inclined lower surfaces of said adjustable top for elevating the adjustable top to correspond to the horizontal movement of said adjustable member.

2. A bearing trimmer comprising a frame, a stationary table mounted thereon provided with an opening, a movable top vertically adjustable in said opening and formed with parallel inclined portions on the lower side thereof, transverse supporting members secured to said table and disposed below the inclined portions of said top, and an adjusting element provided with a pair of parallel wedges slidably mounted on said sup-

porting members and having inclined upper surfaces engaging the inclined portions of said top for elevating said top to an extent to correspond to the horizontal movement of said wedges.

3. A bearing trimmer comprising a frame, a stationary table mounted thereon provided with an opening, a movable top vertically adjustable in said opening and formed with parallel inclined portions on the lower side thereof, transverse supporting members secured to said table and disposed below the inclined portions of said top, an adjusting element provided with a pair of parallel wedges slidably mounted on said supporting members and having inclined upper surfaces engaging the inclined portions of said top for elevating said top to an extent to correspond to the horizontal movement of said wedges, and manually operable means mounted on said frame and connected with and for operating said adjusting element.

4. A bearing trimmer comprising a frame, a stationary table mounted thereon provided with an opening, a movable top vertically adjustable in said opening and formed with parallel inclined portions on the lower side thereof, transverse supporting members secured to said table and disposed below the inclined portions of said top, an adjusting element provided with a pair of parallel wedges slidably mounted on said supporting members and having inclined upper surfaces engaging the inclined portions of said top for elevating said top to an extent to correspond to the horizontal movement of said wedges, the opening in said table comprising a rectangular portion and end extensions, said adjustable top having portions corresponding in form to said end extensions, and a laterally extended portion fitting the rectangular portion of the opening whereby to guide said top in its vertical movement.
